UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,295,866.

Specification of Letters Patent.

Patented Mar. 4, 1919.

Application filed April 26, 1918. Serial No. 230,910.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures, and I do hereby declare the following to be a full, clear, and exact description of the invention, such as 10 will enable others skilled in the art to which it appertains to make and use the same.

This invention relates to improvements in staybolt structures and more particularly to the closure for the bearing sleeve,—the 15 object of the invention being to provide simple and efficient means whereby the cap or closure for the bearing sleeve shall be normally and firmly held to its seat but be permitted to be easily and quickly removed 20 to expose the head of the staybolt for testing purposes.

With this and other objects in view, the invention consists in certain novel features of construction and combinations of parts 25 as hereinafter set forth and pointed out in the claims.

In the accompanying drawings; Figure 1 is a sectional view of a staybolt structure embodying my invention; Fig. 2 is a side 30 elevation; Fig. 3 is a plan view, and Figs. 4, 5, 6 and 7 are views of modifications.

1 represents a bearing sleeve which may be externally threaded and provided internally with a curved surface 2 which serves as a 35 bearing for the rounded or spherical head 3 of a staybolt 4. The outer end portion of the bearing sleeve is provided with a seat 5 for a cap or closure 6,—the latter having, in the construction shown in Figs. 1 to 3, an 40 approximately hemispherical shape and its internal dimensions and configuration are such as to provide suitable clearance for the head of the bolt.

A collar 7 is threaded on the bearing 45 sleeve and made with a hexagonal or other angular external configuration for the reception of a wrench.

The cap 6 is provided at diametrically 50 opposite sides with pairs of perforated lugs or ears 8 and 9 and the collar 7 is provided with an outwardly projecting ear 10 to enter between the lugs 8. A pin 8^a passes through the lugs 8 and through a hole in the ear 10 whereby the cap will be pivotally 55 attached or hinged to the collar,—the holes

in the lugs 8 or the hole in the ear 10 being appreciably larger in diameter than that of the hinge pin so as to provide a loose connection.

A latch 11 has a loose connection with the 60 lugs 9 on the cap by means of a pivot pin 12,—the hook end 13 of said latch being adapted to engage behind the collar 7 and the latter may be notched as at 14 to permit proper engagement of the latch with the 65 collar.

When the parts shall have been assembled and placed in position on the bearing sleeve, as shown in Fig. 1, a further turning force applied to the collar by the application of a 70 suitable wrench, will cause a slight movement of said collar inwardly on the bearing sleeve and the cap 6 to be tightly clamped to its seat.

It will be apparent that when the collar 75 7 is turned in a direction reverse to that above described, the cap will be loosened and may be quickly removed to expose the head of the bolt for testing purposes. It is equally apparent that the cap may be as 80 quickly replaced and clamped onto its seat at the outer end portion of the bearing sleeve.

In the form of the invention shown in Figs. 4 and 5, the cap is provided with a 85 resilient latch 15 which is made integral with said cap, instead of employing a pivoted latch as shown in Figs. 1 and 3.

In the form of invention illustrated in Figs. 6 and 7, a plate cap 16 instead of a 90 hemi-spherical cap is shown and provided on its top with perforated lugs 17, between which the intermediate portion of a bar 18 is loosely pivoted by means of a pivot pin 19. One end of this bar is provided with 95 an arm 20 having a loose pivotal connection with a lug 21 projecting laterally from the collar 7. The other end of the bar 18 is bent to form a latch member 22, the lip 23 of which engages behind the collar 7. 100

Having fully described my invention, what I claim as new and desire to secure by Letters Patent, is:—

1. In a staybolt structure, the combination with a bearing sleeve, and a collar 105 threaded thereon, of a cap for closing said sleeve having pivotal connection with said collar, and a latch member projecting from said cap and adapted to engage behind said collar.

2. In a staybolt structure, the combination with a bearing sleeve and a collar threaded on said sleeve, of a cap for closing said sleeve, said cap having pivotal connection with said collar, and a latch pivoted to said cap and adapted to engage behind said collar.

3. In a staybolt structure, the combination with a bearing sleeve, of a cap to seat thereon and having lugs at diametrically opposite sides, a collar threaded on the bearing sleeve and having an outwardly projecting ear, a pivot pin loosely connecting said

ear with the lug at one side of the cap, and a latch having a loose pivotal connection 15 with the lug at the other side of the cap and adapted to engage behind the threaded collar.

In testimony whereof I have signed this specification in the presence of two subscr- 20
ing witnesses.

ETHAN I. DODDS.
